UNITED STATES PATENT OFFICE.

HARRY GERSTEIN, OF ARVERNE, AND FRANK GERSTEIN, OF NEW YORK, N. Y.

SHOULDER STRAP.

Application filed November 22, 1921. Serial No. 516,512.

To all whom it may concern:

Be it known that we, HARRY GERSTEIN, a citizen of the United States, residing at Arverne, county of Queens, State of New York, and FRANK GERSTEIN, a citizen of the United States, residing in the borough of Bronx, county of Bronx, and State of New York, have invented certain new and useful Improvements in Shoulder Straps, of which the following is a specification.

This invention relates to shoulder straps for brassières, and has for its primary object the provision of such an article sufficiently resilient to permit freedom of movement of the body without exerting undue strains or stresses upon the garment to which the strap embodying our invention is attached.

A further object of our invention is to so construct a strap having the necessary resilient characteristics as to present a neat and attractive appearance when incorporated into the garment with which the strap is particularly adapted to be used.

Further objects of our invention will become apparent from the following description taken in connection with the drawings in which:

Figure 1 is a face view of the body structure of a strap embodying our invention.

Figure 2 is a similar view to that of Figure 1 in which the body structure is shown as stretched or extended and covered with a suitable material while so extended.

Figure 3 is a face view of the strap embodying our invention, the same being shown as retracted to normal length.

The body structure illustrated in Figure 1 which we employ in building up a strap embodying our invention, is composed of an intermediate section 5 of inelastic material, such as any suitable quality of cloth fabric or other flexible material, to the ends of which are sewed or stitched tabs 6 of suitable elastic tape. The intermediate section 5 and the tabs 6 are of such lengths as may be required for the particular garment with which the strap is intended to be used, the

length of the intermediate section 5 or that of the tabs 6 being determined to some extent upon the degree of elasticity required in the finished article.

After the tabs 6 have been suitably secured to the intermediate section 5, the body structure thus formed is placed under tension causing the tabs 6 to stretch, whereupon the structure while held taut, is covered with a suitable binding or covering 7 of fabric or other flexible material which is stitched at its meeting longitudinal edges 8, to the body structure as shown in Figure 2.

A strap constructed in accordance with our invention is such, as illustrated in Figure 3, that the covering 7 at the ends thereof is so folded or Shirred as to permit the elastic to readily contract or lengthen as the case may require when the strap is incorporated into such garments as are particularly adapted to be used in connection therewith.

If having thus described our invention what we claim is:

A shoulder strap comprising an inelastic flexible intermediate section, elastic tabs connected to said intermediate section at opposite ends thereof, a covering enclosing said intermediate section and having its longitudinal edges overlapped approximately at the longitudinal centre of the strap and a line of stitching passed through said overlapped edges, said intermediate section and said tabs thereby attaching said overlapping edges to each other, to said intermediate section and to said tabs, that portion of said covering enclosing said tabs being normally in a shirred condition to permit the elastic tabs to yield with respect to said intermediate section and relieve that portion of said covering which encloses said intermediate section of any undue strain when said tabs are extended under tension.

In testimony whereof, we have affixed our signatures to this specification.

HARRY GERSTEIN.
FRANK GERSTEIN.
